(57) **CLAIM**

The ornamental design for an ceiling fan blade assembly, as shown and described.

DESCRIPTION

FIG. 1 is a perspective view from below of the ceiling fan blade assembly in accordance with my design, illustrating the environment of the invention;

FIG. 2 is a bottom plan view on a reduced scale of the ceiling fan blade assembly in accordance with my design, illustrating the environment of the invention;

FIG. 3 is a front view on a reduced scale of the ceiling fan blade assembly in accordance with my design, illustrating the environment of the invention;

FIG. 4 is a top plan view on a reduced scale of the ceiling fan blade assembly in accordance with my design, illustrating the environment of the invention;

FIG. 5 is a side elevation view on a reduced scale of the ceiling fan blade assembly in accordance with my design, the opposite side being substantially identical to that shown, illustrating the environment of the invention;

FIG. 6 is an enlarged top plan view of the ceiling fan blade assembly in accordance with my design;

FIG. 7 is an enlarged bottom plan view of the ceiling fan blade assembly in accordance with my design;

FIG. 8 is an enlarged end view of the ceiling fan blade assembly in accordance with my design;

FIG. 9 is an enlarged left elevation view of the ceiling fan blade assembly in accordance with my design; and,

FIG. 10 is an enlarged right elevation view of the ceiling fan blade assembly in accordance with my design.

The broken line showing of environmental structure in FIGS. 1-10 is for illustrative purposes only and forms no part of the claimed design.

The blade is shown broken away in FIGS. 1, 3 and 6-10.
